CLAIM

The ornamental design for a flip lid tumbler, as shown and described.

DESCRIPTION

FIG. 1 is a top perspective view of a first embodiment of a flip lid tumbler, showing my new design.

FIG. 2 is a bottom perspective view of FIG. 1.

FIG. 3 is a front side elevation view of FIG. 1.

FIG. 4 is a rear side elevation view of FIG. 1.

FIG. 5 is a right side elevation view of FIG. 1.

FIG. 6 is a left side elevation view of FIG. 1.

FIG. 7 is a top view of FIG. 1.

FIG. 8 is a bottom view of FIG. 1; and,

FIG. 9 is a right side view of a second embodiment of a flip lid tumbler, showing my new design.

The broken lines in the figures illustrate the portions of the flip lid tumbler that form no part of the claims design.
